UNITED STATES PATENT OFFICE

103,162

DESIGN FOR A TIMER CASE

John P. Rainbault, New York, N. Y., assignor to
General Electric Company, a corporation of
New York

Application December 18, 1936, Serial No. 66,631

Term of patent 14 years

To all whom it may concern:

Be it known that I, John P. Rainbault, a citizen of the United States, residing at New York, in the county of New York, State of New York, have invented a new, original, and ornamental Design for a Timer Case, of which the following is a specification, reference being had to the

accompanying drawing, forming a part thereof.

Fig. 1 is a front view of a timer case showing my new design, and Fig. 2 is a side view thereof.

I claim:

The ornamental design for a timer case as shown.

JOHN P. RAINBAULT.
